UNITED STATES PATENT OFFICE.

JOSEPH L. BANGLEY, OF NORFOLK, VIRGINIA, ASSIGNOR OF ONE-HALF TO
HARRY SMITH, OF SAME PLACE.

DESIGN FOR A PRINTING-DEVICE FRAME FOR PAPER-ROLL HOLDERS.

SPECIFICATION forming part of Design No. 30,423, dated March 28, 1899.

Application filed March 3, 1899. Serial No. 707,682. Term of patent 14 years.

To all whom it may concern:

Be it known that I, JOSEPH L. BANGLEY, a citizen of the United States, residing at Norfolk, in the county of Norfolk and State of Virginia, have invented and produced a new and original Design for a Printing-Device Frame for Paper-Roll Holders, of which the following is a specification.

This invention relates to a new and original design for a printing-device frame for paper-roll holders; and it has for its object to provide a design of this character that shall be both useful and ornamental.

The leading feature of the design resides in a substantially U-shaped yoke provided at one side with a pair of parallel straight arms extended, respectively, from the opposite side members of the yoke, the latter being further provided with a single offstanding supporting-tongue projected centrally from the cross-bar thereof at the side opposite said straight arms.

One minor feature of the design is the U-shaped yoke, having the side members thereof provided with rounded terminal extensions projecting beyond the connection of the parallel arms with the yoke and also provided with concavities in their edges opposite said arms.

Additional minor features of the design are the parallel arms, being disposed at approximately right angles to the plane of the yoke and provided in their outer ends with inclined or oblique slots and the said offstanding supporting-tongue being provided at its outer end beyond its connection with the yoke with a substantially U-shaped clip portion.

In the drawings, Figure 1 is a perspective view of a printing-device frame embodying the herein-described design. Fig. 2 is a ver-

tical sectional view thereof. Fig. 3 is an elevation of the same.

Referring to the accompanying drawings, the numeral 1 designates a substantially U-shaped frame having a rounded or convexed exterior surface and provided at one side with a pair of parallel straight arms 2, extended, respectively, from the opposite parallel side members of the yoke. The said arms 2 are disposed at approximately right angles to the plane of the yoke 1 and are provided in their outer ends with the inclined or oblique slots 3, and the said yoke 1 is further provided with shallow concavities 4, formed in the edges thereof opposite the inner ends of the arms 2, which connect with the yoke. In addition to the features described the substantially U-shaped yoke 1 has the parallel side members thereof provided with the rounded terminal extensions 5, which project beyond the connection of the parallel arms 2 therewith. Projected centrally from the cross-bar of the yoke 1 is a cross-sectional flat supporting-tongue 6. The supporting-tongue 6 is extended from the yoke at the side thereof opposite the parallel arms 2 and is provided at its outer end with a U-shaped clip portion 7, which completes the characteristic features of the design.

What is claimed is—

The design for a printing-device frame for paper-roll holders, as herein shown and described.

In testimony that I claim the foregoing as my own I have hereto affixed my signature in the presence of two witnesses.

JOSEPH L. BANGLEY.
